UNITED STATES PATENT OFFICE.

JOHN D. HILLIARD, JR., OF GLENS FALLS, NEW YORK, ASSIGNOR TO
GENERAL ELECTRIC COMPANY, A CORPORATION OF NEW YORK.

AUTOMATIC UNLOCKING DEVICE FOR SWITCH MECHANISMS.

No. 832,729.

Specification of Letters Patent.

Patented Oct. 9, 1906.

Application filed April 20, 1904. Serial No. 204,074.

To all whom it may concern:

Be it known that I, JOHN D. HILLIARD, JR., a citizen of the United States, residing at Glens Falls, county of Warren, State of New York, have invented certain new and useful Improvements in Automatic Unlocking Devices for Switch Mechanisms, of which the following is a specification.

This invention relates to switching mechanism for connecting a polyphase alternating current machine with bus-bars to which other machines are connected in parallel. In such an operation it is very necessary that the machine to be connected be running at the same speed and in phase with the other machine or machines.

The object of my invention is to keep the switch locked until it is safe to close it and then unlock it automatically. This is preferably accomplished by means of a latch which engages with the switch-actuating mechanism until it is withdrawn by a solenoid energized by current in one or more legs of the polyphase system.

In the accompanying drawings, Figure 1 is a diagram showing my invention applied to a three-phase system. Figs. 2 and 3 are diagrams showing two other modes of energizing the unlocking-solenoid, and Fig. 4 is a side elevation of the modified form of each used in Figs. 2 and 3 shown on a larger scale.

The bus-bars 1, 2, and 3 are supposed to be conveying current generated by one or more machines, (not shown,) and it is desired to connect the generator 4 to said bars by means of the triple-pole switch 5. Said switch is opened and closed by a hand-lever 6, connected with the switch-blades in any suitable manner, as by a connecting-rod 7 and elbow-lever 8. Adjacent to the lever is a solenoid 9, whose movable core is connected with a latch 10, preferably pivoted and adapted to engage with a shoulder 11 on the rod 7 and prevent it from being moved to close the switch. Upon energizing the solenoid the latch is lifted. The solenoid is preferably controlled by a relay 9^a in such a way that the solenoid is active when the relay is fully energized.

Referring now to Fig. 1, it will be seen that the machine-leads 1^a 2^a 3^a are open, but that the switch-blade controlling the lead 2^a is shunted by a conductor 2^b, controlled by a switch 12 and containing one or more incan-

descent lamps 13. The switch-blade controlling the lead 3^a is shunted by a conductor 3^b, controlled by a switch 14 and containing the windings of the solenoid 9.

The operation is as follows: The switches 12 and 14 being closed, the machine 4 will supply current to the conductors 2^b and 3^b so long as it is out of phase with the current in the bus-bars. The lamps 13 will therefore flash, the relay 9^a will raise its core, and the solenoid 9 will lift the latch and lock the switch-rod; but as the machine approaches synchronism the lamps 13 will darken, being connected to similar leads of the system, and when the lamps finally become dark and the phases in the solenoid-circuit and the bus-bars coincide, and thus oppose each other, the relay 9^a will be deenergized, opening the circuit of the solenoid 9, the latch 10 will drop, and the switch can be closed. The solenoid 9 may be fed by a potential transformer, as indicated, or by a local source.

In Fig. 2 the solenoid has two windings, one in a cross connection 2^b 3^b between the machine-leads 2^a 3^a and the other in a cross connection 2^c 3^c between the similar bus-bars 2 3. Switches 15 16 control the cross connections. As the machine approaches synchronism the sum of the two fluxes induced by these windings increases until at the point when the switch can be safely closed it becomes sufficient to lift the latch and release the switch-rod 7. The solenoid 9 is here shown, as also in Fig. 3, as directly included in the synchronizing-circuit. In practice it may be preferable to control it by a relay, as in Fig. 1, for increased sensitivity of action.

In Fig. 3 a potential transformer 17 is introduced into each cross connection in order to reduce the voltage of the current flowing through the solenoid. By connecting the secondaries of these transformers in series only one winding is necessary on the solenoid. The secondary currents will partially overlap and weaken each other while the machine is out of phase, but when synchronism is reached the two currents will coincide and will strongly energize the solenoid and lift the latch.

Fig. 4 shows the lock used in Figs. 2 and 3. The solenoid is supported by brackets 18 on an upright base 19, through which the rod 7 passes and on which is pivoted the latch 10.

The latch and the shouldered portion of the rod are preferably inclosed by a cover 20 to prevent tampering with them. The lever 6 is conveniently fulcrumed on an arm 21, projecting from the base 19 below the cover.

In accordance with the patent statutes I have described the principle of operation of my invention, together with the apparatus which I now consider to represent the best embodiment thereof; but I desire to have it understood that the apparatus shown is only illustrative and that the invention can be carried out by other means.

What I claim as new, and desire to secure by Letters Patent of the United States, is—

15. The combination with a hand-operated switch free from closing bias for connecting an alternating-current machine with the bus-bars of a distribution system, of a lock for said switch, and an electromagnet controlling said lock and in circuit with said machine.
20. The combination with a hand-operated switch free from closing bias for connecting an alternating-current machine in parallel with the bus-bars of a distribution system, of a lock for said switch, and an electroresponsive device controlling said lock and responsive to coinciding phases of the machine and system.
25. The combination with a switch for connecting an alternating-current machine in parallel with the bus-bars of a distribution system, of a lock for said switch, an electromagnet controlling said lock, a cross connection between different machine-leads, and a similar cross connection between similar bus-bars, both of said connections influencing the electromagnet.
30. The combination with a hand-operated switch free from closing bias for connecting an alternating-current machine in parallel with the bus-bars of a distribution system, of

a lock for said switch, an electromagnet controlling said lock, and cross connections between the machine-leads and the bus-bars 45 coöperating to produce a maximum flux in said magnet.

5. The combination with a switch for connecting an alternating-current machine in parallel with the bus-bars of a distribution system, of cross connections between the machine-leads and the bus-bars, a solenoid whose windings include both cross connections, and a lock for the switch controlled by said solenoid.

6. The combination with a solenoid, of a movable core, a latch pivotally attached thereto, a rod having a shoulder with which said latch engages, and a cover inclosing said latch and the shouldered portion of said rod.

7. In an alternating-current system, a plurality of generators, a common distribution-circuit, a hand-operated switch free from closing bias for cutting into circuit one or more generators, means for normally disabling said switch from closure, and electroresponsive devices for permitting such closure when the phases coincide cross-connected between the machine-leads and the distribution-circuit.

8. The combination with a hand-operated switch free from closing bias for connecting an alternating-current machine with the bus-bars of the distribution-circuit, of a lock for said switch, and an electromagnet controlling said lock and connected in shunt to said switch.

In witness whereof I have hereunto set my hand this 8th day of April, 1904.

JOHN D. HILLIARD, JR.
